HARRY W. McDONALD, OF MINNEAPOLIS, MINNESOTA; CHARLIE McDONALD, OF HOISINGTON, KANSAS; AND EDGAR A. WOLF AND RUDOLPH F. STANEK, OF MORRISTOWN, MINNESOTA, ASSIGNEES, BY MESNE ASSIGNMENTS, TO HARRY W. McDONALD, OF MORRISTOWN, MINNESOTA.

AUTOMATIC MEANS FOR FEEDING CABLES.

Application filed July 13, 1925. Serial No. 43,248.

This invention relates to new and useful improvements in automatic means for feeding cables and more particularly relates to such a device adapted for use in conjunction with the rocking or walking beam of a drilling machine, such as are commonly employed in drilling oil wells and the like.

Drilling machines or apparatus such as are commonly used for drilling oil wells and particularly of the impact type, usually employ a cable for supporting and operating the drill tool or bit, which is adapted to drill into the ground by impacting therewith as a result of the oscillating or rocking movement of the walking beam of the apparatus. The drill cable, as it is commonly termed, must, therefore, be let out or fed from the walking beam at a rate of speed depending upon the speed at which the bit can cut or drill through the particular formation encountered. Such feeding of the drill cable is usually accomplished by the employment of a manually operated device known as a temper-screw, which usually is mounted upon the walking beam, and which must be constantly manipulated by an operator during the drilling operation of the apparatus.

The above described method of manually feeding the drill cable has been found objectionable for various reasons and it is, therefore, desirable that means be provided for automatically feeding the cable a predetermined distance or amount for each stroke of the walking beam.

The novel and improved automatic means for feeding cables featured in this invention is particularly adaptable for use on walking beams to automatically feed the cable therefrom during the operation of drilling a hole or well. The feeding mechanism comprises a cable-gripping device consisting of two endless chains which are mounted upon the feeding end of the walking beam and are arranged to engage each other and to grip the cable therebetween, so that when the chains are actuated or moved, the cable will simultaneously be fed therefrom to lower the drill or bit into the well. The

mechanism provided for actuating the cable-gripping chains is so arranged that upon each downward movement or stroke of the feeding end of the walking beam the chains will automatically be rotated a predetermined distance, thereby automatically feeding the drill cable a distance commensurate with the rotation of the two chains. The feeding mechanism is also mounted entirely upon the walking beam and the support therefor, and is operated by the rocking movement of the beam and therefore does not require any additional power to operate it.

The particular object of the invention, therefore, is to provide an improved automatic means for feeding cables, and more specifically relates to such a device adapted for use to automatically feed the drill-supporting cable of an ordinary drilling apparatus.

Other objects of the invention will appear from the following description and the accompanying drawings and will be pointed out in the annexed claims.

In the drawings there has been disclosed a structure designed to carry out the various objects of the invention, but it is to be understood that the invention is not confined to the exact features shown as various changes may be made within the scope of the claims which follow.

In the accompanying drawings forming part of this specification:

Figure 1 is a view in side elevation showing the invention applied to a rocking beam such as are used on well-drilling machinery;

Figure 2 is a sectional plan view on the line 2-2 of Figure 1 showing the means provided for varying or adjusting the feed of the cable;

Figure 3 is a vertical detail sectional view on the line 3-3 of Figures 1 and 2;

Figure 4 is an enlarged side elevation of the device as mounted upon a rocking beam;

Figure 5 is a sectional plan view on the line 5-5 of Figure 4;

Figure 6 is a sectional plan view on the line 6-6 of Figure 4, showing the means

provided for controlling the automatic feeding of the cable;

Figure 7 is a side elevation of a drilling machine and derrick, showing the invention applied to the rocking beam of the drilling machine;

Figure 8 is a detail sectional view on the line 8—8 of Figure 9, showing the means provided for gripping the cable;

10 Figure 9 is a sectional plan view on the line 9—9 of Figure 9;

Figure 10 is a sectional view on the line 10—10 of Figure 8;

15 Figure 11 is an enlarged detail sectional view showing how the cable is clamped between the movable chain sections;

Figure 12 is a sectional plan view on the line 12—12 of Figure 11, and

20 Figure 13 is a detail view showing a portion of one of the clamping chains.

In the selected embodiment of the invention here shown there is illustrated a walking beam 16, such as is commonly employed in well drilling machinery for operating the 25 tool or bit. The beam preferably consists of a pair of bars secured together in spaced relation by means of spacing blocks or channels 17 as shown in Figure 5. A bearing bracket 18 is secured to the lower face of 30 the beam 16 by suitable bolts 19, and is adapted to be seated in a bearing cap 21 mounted upon and secured to a standard or supporting post 22 as shown in Figure 1. A connecting rod 23 operatively connects one 35 end of the beam 16 with the crank pin 24 mounted in the usual bull wheel 25 of a drilling machine 26, as shown in Figure 7. When the bull wheel 25 is rotated, a rocking movement will be imparted to the walking beam 16 as is common in structures of this 40 type.

The automatic feeding means forming the subject matter of the invention is mounted upon the outer end of the walking beam and 45 preferably comprises a pair of endless chains 27 and 28, rotatably mounted thereon and having adjacent sections thereof adapted to engage each other and to securely grip or clamp the cable therebetween (see Figures 50 1, 8 and 11).

The main drive chain 27 is mounted upon a drive sprocket 29 rotatably mounted upon a short stud or shaft 31 mounted in bearings 32 and 33, terminally provided on the extensions 34 of a bracket 35 secured to the feeding end of the walking beam by means of rivets 36. A pair of idler rollers 37 and 38 are mounted in the bracket 35 and over which the main feeding chain 27 passes as shown in 55 Figure 8. A run-way 39, preferably integral with the bracket 35, is interposed between the rollers 37 and 38 to provide a backing or support for the effective cable-gripping portion of the chain. The lower

65 idler roller 38 is preferably mounted in bearing blocks 41, which preferably are adjustably mounted in suitable guides in the bracket 35 and are adapted to be locked in adjusted position by means of adjusting screws 42 (see Figure 8).

70 The complementary cable-gripping chain 28 is preferably mounted upon a pair of idler sprockets 43 rotatively mounted upon studs or pins 44 borne by a bracket 45, which is provided with lugs 46 and 47, whereby it may be pivotally connected to an intermediate supporting member 48 by means of pivot pins 49, which preferably is adjustably mounted upon the bracket 35 by means of adjusting screws 51, as shown in Figure 4. 80 The adjusting screws 51 provide means for adjusting the complementary chain 28 with relation to the vertical section of the drive chain 27 so as to adapt the cable-gripping means for cables of various sizes.

85 The bracket 45, supporting the complementary chain 28, is adapted to be oscillated upon the pivot pins 49 from the full to the dotted line position in Figure 9, so that the drill cable 52 may conveniently be inserted between the two adjacent gripping portions of the chains 27 and 28. The means provided for locking the bracket 45 and, therefore, the complementary chain 28, in operative position, as shown in full line in Figure 9, preferably consists of a locking lever 53 pivotally connected to the bracket 45 by means of links 54 and an adjusting screw 55. One end of the lever 53 is adapted to engage a hook 56 formed in the bracket 35 whereby the bracket 45 may be securely locked to the bracket 35 as shown in Figure 9. The lever 53 is so formed that when it is in the position shown in full lines (Figure 9) the outer or grip end 57 thereof will be forcibly held 105 against the side of the beam 16 as a result of the bearing point at the opposite end thereof being out of alignment with the pivot pins 58 connecting the lever to the links 54 and the adjusting screw 55. When the grip portion 57 of the lever 53 is moved upwardly away from the beam 16, the opposite end thereof may be disengaged from the hook 56 after which the bracket 45 may be conveniently swung to the dotted line position 110 shown in Figure 9, and the drill cable 52 inserted between or removed from between the two chains. The bracket 45 supporting the complementary chain 28, is preferably provided with an overhanging hook or portion 115 59 adapted to engage the upper face of the bracket 35, thereby to take up some of the downward thrust exerted against the bracket 35, when the chain 28 is clamped against the drill cable and the adjacent vertical portion of the main drive chain 27. The bracket 45 is also provided with a run-way 61 adapted 120 to receive the vertical portion of the chain

28 adjacent the vertical section of the drive chain 27, so that when the two chains are operatively connected together as shown in Figures 8 and 9, the adjacent vertical sections thereof will be supported by the run-ways 39 and 61, and will thereby be prevented from spreading and will securely clamp the cable therebetween substantially the full length of the adjacent vertical sections, as particularly shown in Figure 8.

The means provided for intermittently actuating the drive chain 27 preferably consists of a drive mechanism mounted adjacent the bracket 18 forming the supporting means for the walking beam 16, as shown in Figures 4, and 5. A worm wheel 62 is mounted upon and secured to the drive sprocket 29 and is adapted to intermesh with a worm 63 secured to the shaft 64 having one end rotatably mounted in a thrust bearing 65 secured to one of the side members of the walking beam 16, adjacent the sprocket 29, and its opposite end similarly mounted in a bearing bracket 66, also secured to the side member of the walking beam.

A bevel gear 67 is secured to the end of the shaft 64 adjacent the bearing 66 and intermeshes with a similar pinion 68 provided on a gear wheel 69, as particularly shown in Figure 5. A small pinion 71 is also provided on the gear 69 adapted to mesh with a similar gear 72 rotatably mounted upon a shaft 73 which is supported by the side members of the beam 16. The gear wheel 69 also meshes with a pinion 74 preferably integrally formed upon a ratchet wheel 75, which also is rotatably mounted upon the shaft 73. A collar 76 may be secured to the shaft 73 to retain the gear wheel 72 and the ratchet wheel 75 in their proper positions thereon. A relatively smaller ratchet wheel 77 is secured to the gear wheel 72 as shown. These two ratchet wheels 75 and 77 are adapted to be selectively engaged by a pair of rack bars 78 and 79, as shown in Figure 4.

The rack bars or oscillatable ratchet driving members 78 and 79 are mounted upon a pin 81 secured to the upper forked end portion 82 of a threaded stud 83, mounted on a threaded sleeve 84, rotatably mounted on a bracket 85, secured to the upright supporting post 22, upon which the walking beam 16 is mounted. An annular flange 86 is provided upon the upper end of the sleeve 84 adapted to be seated in a recess provided in the bearing bracket 85, thereby to lock the bearing sleeve 84 against longitudinal movement. A retaining collar 87 is secured to the upper face of the bearing bracket 85, by means of bolts 88, and has a key member 89 fixedly mounted therein adapted to engage a key-way 91 provided in the threaded stud 83 as shown in Figures 1,

2 and 3. The purpose of the key 89 and the key-way 91 is to prevent the stud 83 from relatively rotating when the threaded sleeve 84 is rotated in its bearings, thereby causing the stud 83, and therefore the rack bars 78 and 79, to be relatively raised or lowered each time the threaded sleeve 84 is rotated. The sleeve 84 may be conveniently rotated by means of a crank 92 secured to the operating rod 93, which is connected to the upright shaft 94 by means of a universal joint or connection 95 as shown in Figures 1 and 3. A pinion 96 is secured to the shaft 94 and meshes with a gear 97 secured to the threaded sleeve 84 so that when the shaft 94 is rotated, a rotary movement will be imparted to the sleeve 84 with the resultant raising and lowering of the threaded stud or stem 83 mounted therein, and, therefore, the rack bars 78 and 79. The crank 92 may be so arranged and mounted that the raising and lowering of the rack bars may be conveniently performed by an operator standing upon the ground adjacent the drilling machine.

When the rack bar 78 is in engagement with its complementary ratchet wheel 75, as shown in Figure 1, a rotary movement will be transmitted to the ratchet wheel 75 at each stroke of the walking beam, or each time the feeding end thereof is moved downwardly from the full to the dotted line position shown in Figure 1. Such relative movement of the ratchet wheel 75 upon the shaft 73 will be caused as a result of the teeth of the ratchet and also of the rack bar being so shaped that when in engagement with each other as shown and the feeding end of the walking beam is moved downwardly the ratchet wheel will substantially roll in the rack bar, thereby causing it to be rotated upon the shaft 73, which in turn will cause the gear wheel 69 to be rotated in the opposite direction as a result of it being in mesh with the pinion 74 secured to the ratchet wheel 75. Such rotation of the gear wheel 69 will transmit a rotary movement to the worm shaft 68 as a result of its connection therewith through the bevel pinion 68 and gear 67, thereby causing the drive sprocket 29 to be rotated with the resultant rotation of the drive chain 27. Upon the upstroke of the feeding end of the walking beam the teeth of the ratchet wheel will slide over the teeth in the rack bar until the beam starts its next downward stroke when the ratchet wheel will again be rotated as a result of its connection with the rack bar 78.

By this novel arrangement it will readily be seen that no additional power will be required to operate the cable-feeding mechanism, as such operation is accomplished entirely by the rocking movement of the walking beam. By relatively raising or lowering

the rack bar 78, by adjusting the position of the stud 83 in the threaded sleeve 84, more or less teeth may be caused to engage the ratchet wheel, thereby increasing or decreasing the amount of rotation of the ratchet wheel and therefore the cable-feeding chains 27 and 28.

The purpose of the rack bar 79 and ratchet wheel 77 is to increase the feed of the drill cable. When the high speed rack bar 79 is in engagement with the ratchet wheel 77 as shown in Figure 4, the slow speed rack bar 78 will be moved out of engagement with its complementary rack or ratchet 75 as shown, thereby causing the ratchet 77 to be similarly intermittently rotated at each stroke of the walking beam.

Referring to Figure 5 it will be noted that the ratchet wheel 77 is secured to the gear wheel 72 and, therefore, when the ratchet is rotated a similar movement will be transmitted to the gear wheel 72 which in turn will cause the pinion 71 in mesh therewith, to be rotated in the opposite direction. Such rotation of the pinion 71 will cause the worm shaft 64 to be rotated by means of the beveled gears 67 and 68, thereby transmitting power to the drive shaft sprocket upon which the chain 27 is mounted. When the high speed ratchet 79 and ratchet wheel 77 are functioning, the speed of the worm shaft 64 will be considerably increased as a result of the relatively larger gear wheel 72 operating the pinion 71 and, therefore, the beveled pinion 68. When the slow speed rack 78 is operatively connected to the ratchet wheel 75, as shown in Figure 1, the speed of the worm shaft 64 will be relatively slower as a result of the power being transmitted from the relatively small pinion 74 to the gear wheel 69, which will cause the beveled pinion 68, and therefore the worm shaft 64, to be rotated at a relatively slower speed. By relatively raising or lowering the racks 78 and 79 the feed of the drill cable may be varied and adjusted to suit practically all conditions of drilling, as, for instance, when drilling in a very hard formation the feed of the drill may be extremely slow, and when drilling in a soft formation such as sand, the feed of the cable will be relatively faster.

Means are provided for selectively moving the racks 78 and 79 in and out of driving connection with their complementary ratchet wheels 75 and 77. Such means preferably consists of a hand lever 98 mounted upon the lower end of the high speed ratchet bar 79. The slower speed ratchet 78 is provided with a quadrant 99 adapted to be engaged by a dog 101, mounted upon the operating lever 98, as shown in Figures 1 and 4. A tension spring 102 has one end connected to the rack bar 78 and its other end connected to a right-angled bracket 103 having its lower end secured to the forked head 82 of the

threaded stud 83 as shown. This spring tends to pull the rack bar towards the ratchet wheels 75 and 77, so that when the operating lever 98 is operated either one or the other of the rack bars will be yieldably moved into driving connection with its complementary rack, as shown in Figures 1 and 4. A latch 104 is pivotally mounted upon the head 82 and is adapted to engage the upper portion of the quadrant 99, thereby to retain the two rack bars in an inoperative position out of driving connection with the ratchets 75 and 77. The gravity operable latch 104 is provided with a shoulder 120, adapted to about a corresponding shoulder 121 of the quadrant 99 when the lever 98 is forced downwardly from its position in Fig. 6. This movement lowers the quadrant and throws racks 78 and 79 away from wheels 75 and 77 to non-operative positions. When it is desired to move rack 79 to non-feeding position, the lever detent 101 is released, and the lever forced downwardly, after which the detent is engaged in a lower notch as in Fig. 1. The spring 102 will draw rack 78 to ratchet wheel engaging position.

Another feature of this invention resides in the novel construction of the links from which the two feed chains 27 and 28 are constructed. By reference to Figures 11, 12 and 13 it will be noted that each link is provided with a recess or groove 105, which is so arranged that a bore or socket will be provided between the adjacent vertical sections of the two chains 27 and 28 adapted to receive the drill cable 52, as particularly shown in Figures 11 and 12. The grooves or recesses 105 in the links are so formed that when the links are aligned between the two run-ways 39 and 61 as shown in Figure 11, the aligned grooves will provide a wave-like bore in which the drill cable will be securely clamped.

The links of each chain are also provided with a plurality of spaced teeth 106 adapted to intermesh with similar teeth provided upon the opposed links of its complementary chain, thereby locking together the adjacent vertical sections of the feed chains for operation as a unit, when traveling between the run-ways 39 and 61, as shown. Anti-friction rollers are provided upon the connecting pins 108 between the chain links to take up the outward thrust exerted against the run-ways 39 and 61 when the cable is clamped between the vertical chain sections during the feeding operation of the cable. By means of this novel chain construction it will be readily seen that when the cable is clamped or gripped between the two vertical sections of the chains 27 and 28, it will be securely held therebetween so as to move synchronously therewith. By means of the adjusting screws 51 and the adjustment of the threaded stud 55 in the bracket 45, the

distance between the adjacent vertical sections of the chains 27 and 28 may be adjusted and varied to suit the size or diameter of the drill cable used.

- 5 In the operation of this novel automatic means for feeding cables, and when used in connection with the walking beam of a drilling machine as shown in the accompanying drawings, the drill cable passes from one of 10 the drums of the drilling machine 26, as shown in Figure 7, over a sheave 109, mounted on top of the usual derrick 111; thence downwardly therefrom and between the two feed chains 27 and 28, and into the bored 15 hole in the ground where its lower end is secured to the rope-socket or drill stem of the usual boring tool or bit (not shown). This feeding mechanism is particularly adapted for use in connection with the well-known 20 mud-laden fluid system of drilling, wherein a mud-laden fluid is delivered to the bottom of the well or hole by means of a flexible or non-flexible steel water line or hose. In Figure 7 the use of a flexible steel water 25 line 112 is shown to deliver the fluid to the bottom of the well. This water line passes over a sheave 113 mounted upon a bracket 114 secured to the feeding mechanism as particularly shown in Figures 1 and 8. The 30 steel water line is mounted upon a drum 115 which is adapted to feed the water line into the well simultaneously with the feeding of the drill cable 52.

When starting to bore a hole or well in 35 the ground the drilling tool is first spudded-in or sunk into the ground in the usual manner until it has been lowered to a point substantially below the surface of the ground level. The automatic feeding 40 mechanism is usually not employed during the spudding-in operation of the drill tool, but as soon as the tool has been lowered to the position above described, the drill cable 52 will be clamped between the 45 two feed chains 27 and 28 as hereinbefore described, after which the connecting rod 23 is operatively connected to the crank pin 24 of the bull wheel 25, and the walking beam 16 actuated to operate the drill tool in the 50 usual manner. One of the rack bars is then moved into engagement with its complementary ratchet wheel, thereby causing each 55 downward stroke or movement of the feeding end of the walking beam to transmit an intermittent feeding movement to the drill cable. Such automatic feeding of the cable may be varied while the machine is in operation, to suit the particular formation of the material being drilled. By thus enabling 60 the operator to increase or decrease the feeding of the drill cable while the machine is in operation, a great saving of time is effected as compared with the present method of manually feeding the drill cable by the 65 use of the well-known temper-screw now commonly employed for such purposes. Also by firmly gripping the cable between the two feed chains 27 and 28, the danger of injuring the cable is considerably minimized.

The feeding mechanism may be employed 70 for various purposes where it is desired to automatically feed a cable, but it is particularly adapted for use in connection with drilling machines of ordinary construction, and which, when mounted thereon, will convert such an apparatus of the hand-operated type into an automatic feeding apparatus, which will be positive and fool-proof in operation.

Having thus described our invention what 80 we claim as new and desire to secure by Letters Patent is:

1. A cable feeding means, comprising flexible members movable in unison, said members having transversely concaved gripping 85 surfaces, undulating in direction of feed, co-operable for gripping a cable.

2. A cable feeding means, comprising belt members interlockingly cooperable for movement in unison, and having concaved and undulating surfaces cooperable for gripping a cable, and means for operating one of the 90 members to drive the other.

3. A cable feeding means comprising co-operating belts having gripping surfaces between which the cable is gripped, and means for intermittently operating said belts to feed the cable.

4. A cable feeding means comprising flexible traveling members between which the 100 cable is gripped, and means for automatically operating said members, said traveling members interlockable to prevent independent movement.

5. A cable feeding means comprising flexible traveling members between which the 105 cable is gripped, and means for automatically operating said members, said traveling members having a series of intermeshing teeth to prevent independent movement.

6. A cable feeding means comprising co-operating belts having interlockable links provided with gripping surfaces adapted to engage and feed a cable, and means for operating said belts.

7. A cable feeding means comprising co-operating flexible members having undulating gripping surfaces adapted to engage and feed a cable, and means for operating said members.

8. In a well-digging apparatus, an oscillating beam, a drill-supporting cable, means mounted on said beam for engaging and feeding said cable and mechanism actuated by the oscillation of said beam for operating said feeding means.

9. In a well-digging apparatus, an oscillating beam, a drill-supporting cable, traveling members having comparatively long gripping surfaces between which said cable 130

is gripped and held, and mechanism actuated by the oscillation of said beam for operating said feeding means.

10. A well-digging apparatus comprising an oscillating beam, a drill-supporting cable, belts mounted on said beam and having cooperating gripping jaws between which the cable is held and fed, and mechanism for intermittently operating said belts.

11. A well-digging apparatus comprising an oscillating beam, a drill-supporting cable, a belt mounted lengthwise of said beam at one end thereof, a second belt mounted transversely of said beam, said belts having cooperating jaws between which the cable is gripped and held, and mechanism operated intermittently by the oscillation of said beam for operating said belt.

12. A well-drilling apparatus including an oscillating beam and a drill-supporting cable, cooperating flexible members mounted on said beam and having gripping surfaces between which the cable is held and fed, and a ratchet device adapted to intermittently operate said flexible members to feed the cable.

13. A well-drilling apparatus, including an oscillating beam, a drill-supporting cable, cooperating belts mounted on said beam and having undulating gripping surfaces between which the cable is held and fed, and a ratchet device adapted intermittently to operate said belts to feed the cable when the beam is oscillated.

14. A well-drilling apparatus including a rocking beam and a drill-supporting cable, flexible members mounted on said beam and having cooperating gripping surfaces between which the cable is held and fed, means to prevent independent movement of said members, and a ratchet device adapted automatically to intermittently operate said members to feed the cable when said beam is rocked.

15. A well-drilling apparatus including a rocking beam and support therefor, a drill-supporting cable, cooperating belts mounted on said beam and having undulating and concaval gripping surfaces adapted to grip and feed the cable, a ratchet device for intermittently operating said belts to feed the cable when said beam is rocked, said ratchet device comprising ratchet wheels mounted on said beam, adapted to be engaged by rack bars mounted on said beam support.

16. A well-drilling apparatus including an oscillating beam and a support therefor, a drill-supporting cable, cooperating flexible members mounted on said beam and having gripping surfaces between which the cable is gripped and fed, a ratchet device for automatically operating said flexible members to intermittently feed the cable, said ratchet device comprising a pair of ratchet wheels mounted on said beam and a pair of rack

bars mounted upon said beam support and engaging said wheels, a driving connection between said ratchet wheels and said flexible members, and means for selectively moving said rack bars into driving connection with said ratchet wheels whereby, upon oscillation of said beam, said flexible members will be automatically and intermittently operated to vary the feed of the cable.

17. A well-drilling apparatus comprising an oscillating beam and a support therefor, a drill-supporting cable, link belts mounted on said beam and having cooperating gripping surfaces between which the cable is held and fed, a ratchet device for intermittently operating said belts to feed the cable comprising ratchet wheels mounted on said beam and complementary rack bars mounted on said beam support and engaging said wheels, and means for relatively adjusting the position of said rack bars to vary the feed of the cable.

18. A well-digging apparatus, comprising an oscillatable beam, complemental cable-gripping chains, separately supported upon the beam having their links interlockingly engageable throughout a cable-gripping zone, for causing chain movement in unison, said chains adapted to surround, grip, support and feed the cable, means to prevent spreading movements of the chains in the cable gripping zone for positively maintaining the interlocked relation of the links, and mechanism for intermittently operating one of the belts.

19. A well-digging apparatus, comprising an oscillatable beam, complemental cable-gripping chains, having their links interlockingly engageable throughout a cable-gripping zone for obtaining movement of said chains in unison, the chains adapted to surround, grip and feed the cable, guides to prevent spreading movements of the chains in the cable-gripping zone for maintaining the interlocked relation of the links, mechanism for imparting feed movements to one of the chains, said mechanism comprising feed gearing upon the beam transmittably connected with one of the chains, including a plurality of driving ratchet wheels of different diameters, and corresponding oscillatable toothed ratchet wheel driving members, mounted independently of the beam, one for each wheel, engageable therewith, for obtaining selective feed movements of the ratchet wheels.

20. A well-digging apparatus comprising an oscillatable beam, complemental cable-gripping chains, each independently supported upon the beam, having their links interlockingly engageable throughout a cable-gripping zone for driving one chain by the other, means to prevent spreading movements of the chains in the cable-gripping zone, for positively maintaining the inter-

locked relation of the links, and ratchet feed mechanism operable by the rocking motions of the walking beam for obtaining intermittent cable feed movements in correspondence to the cutting rates of the drill.

21. A cable-feeding apparatus for a well-digging machine, comprising an oscillatable beam, complemental cable-gripping chains upon the beam, the links of the chains having teeth and the teeth of the chains interlockingly engageable throughout a cable-gripping zone for chain movement in unison, said links adapted to surround and retain, grip and feed the cable, means to prevent spreading movements of the chains in the cable-gripping zone, for positively maintaining the interlocked relation of the links, and a selective feed rate controlling mechanism transmittably connected with one of the chains operable by the rocking motions of the walking beam.

22. In a device of the class described, a walking beam, a cable feed mechanism upon said walking beam, including a plurality of feed-mechanism driving ratchet wheels, of different diameters, and corresponding toothed ratchet driving wheel members mounted independently of the beam, each alternately engageable with a corresponding ratchet wheel, for obtaining different lengths of feed movement, for the feed mechanism.

23. In a device of the class described, a walking beam, a cable feed mechanism upon said walking beam, including a plurality of feed mechanism driving ratchet wheels of different diameters, and corresponding oscillatable toothed ratchet driving wheel members, mounted independently of the beam, alternately engageable with a corresponding ratchet wheel, for obtaining selective feed movements of the feed mechanism, and means for micrometrically adjusting said ratchet wheel driving members, relative to the wheels for obtaining greater or less degrees of driving engagement of the members with respective wheels.

24. A device of the class described comprising a walking beam having substantially a fixed degree of oscillation, cable feeding instrumentalities upon the beam, including a plurality of ratchet wheels having different diameters, and corresponding ratchet driving members mounted independently of the beam, one for each wheel, each member having teeth engageable with the teeth of the ratchet, said driving members alternately adjustable with reference to the wheels, for permitting a greater or less number of the teeth to be engaged therewith, whereby although the degree of oscillation of the walking beam is fixed, the degree of movement of the feeding device may be selectively lengthened or shortened.

25. A cable feeding means, comprising

complemental flexible traveling members co-operable for gripping a cable, said members interlockingly engageable in a gripping zone for travel in unison, and guides associated with the members throughout the gripping zone to prevent spreading movement of said members.

26. A cable feeding means, comprising flexible traveling members cooperable for gripping a cable, means on the members interlockable for obtaining positive driving of one member by the other, said members adapted to enclose, support and feed a cable, guide means for positively maintaining an interlocked relation of the members in the feeding zone, and means for operating one of the members to drive the other.

27. A well-digging apparatus, including a walking beam having a substantially constant degree of oscillative movement, cable-feeding means upon the beam, mechanism transmittably connected with the feeding means and operable by rocking movements of the beam, including a driving ratchet wheel, and a toothed pawl cooperating with the teeth of the ratchet wheel, said pawl adjustable tangentially of the wheel to engage a greater or less number of teeth therewith.

28. A well-drilling machine including a walking beam, and a drill cable-supporting and feeding device upon the beam, comprising two link belts independently mounted and adjacently disposed, the links of opposite runs of the belts adapted to interlock in a cable-gripping zone for causing one belt to be moved by and in unison with the other, said belts adapted to cooperate for gripping the cable from opposite sides, whereby positive gripping and feeding action is obtained at opposite sides of the belt.

29. A well-drilling machine including a walking beam, and a drill-supporting and feeding device upon the beam, comprising two belts independently mounted and adjacently disposed, the links of opposing runs of the belts adapted to interlock in a cable-gripping zone for causing one belt to be moved by and in unison with the other, said belts adapted to cooperate for gripping the cable from opposite sides, whereby positive gripping and feeding action is obtained at opposite sides of the belt, and guide means for preventing spreading of the belts in the gripping zone.

30. A cable-feeding means comprising two endless link belts, having a portion of their runs cooperable for gripping and feeding a cable, one of said belts supported for movement toward or away from the other to permit of the lateral introduction of a cable therebetween, the belt links having teeth thereon intermeshable for causing the adjustable belt to be driven by the non-adjustable belt.

31. A cable-feeding means comprising complementary link belts having portions cooperable for gripping and feeding a cable, one of said belts pivotally supported for movement toward or away from the other to permit lateral introduction of the cable therebetween, the links of each belt having teeth thereon intermeshable throughout the cable-

gripping zone for causing the adjustable belt to be driven by the non-adjustable belt.

In witness whereof, we have hereunto set our hands this 9th day of July, 1925.

HARRY W. McDONALD.
